UNITED STATES PATENT OFFICE.

DAVID K. STONE, OF BLOOMINGDALE, MICHIGAN.

COIN-CONTROLLED VENDING-MACHINE.

SPECIFICATION forming part of Letters Patent No. 658,517, dated September 25, 1900.

Application filed February 21, 1900. Serial No. 6,083. (No model.)

To all whom it may concern:

Be it known that I, DAVID K. STONE, a citizen of the United States, residing at Bloomingdale, in the county of Van Buren and State 5 of Michigan, have invented certain new and useful Improvements in Coin - Controlled Vending-Machines; and I do hereby declare that the following is a full, clear, and exact description of the same, reference being had 10 to the annexed drawings, making a part of this specification, and to the letters of reference marked thereon.

The present invention has relation to that 15 class of coin-controlled vending-machines wherein goods or articles to be sold are exposed for visual inspection of the customer, who is enabled to make a selection, and through mechanical means such articles thus selected are removed from the machine only 20 after a suitable coin has been deposited in payment therefor.

The purpose of the invention is to materially improve the construction of the above 25 class of machines, whereby it is rendered more effective in its operation, simple in construction, and rendered less liable to become inoperative from any cause.

The invention therefore consists in a coin-controlled vending-machine constructed substantially as shown in the drawings and hereininafter described and claimed.

Figure 1 of the drawings is a perspective view of the complete machine constructed in accordance with my invention; Fig. 2, a vertical section showing the cigar after being selected from the box deposited on the slidable table and previous to being removed from the machine; Fig. 3, a sectional elevation in detail showing the position of the parts of the 35 machine after the coin has been deposited in the hopper; Fig. 4, a horizontal section taken on line 4 4 of Fig. 3; Fig. 5, a vertical section taken on line 5 5 of Fig. 3; Fig. 6, a detail sectional view showing a portion of the 40 top of the show-case and the rotatable rod to which the revolving tray is connected.

In the accompanying drawings, A represents a show-case with glass sides and top, which case may be of any suitable construction and either octagonal or other shape, as 45 found most desirable.

In the drawings I have shown the machine in use for vending such articles as cigars, although it may be used for displaying and vending any goods or articles to which the 55 machine may be found adapted.

The show-case A has a rotatable tray B, which rests on the bottom of the show-case and is provided with an upright rod a, extending up through the top of the case and 60 provided with a hand-wheel b, by which the tray is revolved in the required direction. The tray may be of any suitable shape and of any preferred construction, as may also the rod and hand-wheel, or in place of the hand-wheel any other suitable and well-known means may be used. Several boxes of cigars may be placed upon the tray B to display both light, medium, and strong, or various makes and brands of cigars, as found desirable, and 65 by revolving the tray B the box from which the cigar is to be selected is brought into position, as indicated at C in Fig. 1 of the drawings. When the desired box of cigars is thus brought into position, the cigar is selected 70 and removed by the spring lifting-tongs D and deposited on the table E through the chute F, the cigar thus selected remaining upon the table within the show-case A and prevented from being removed until the required coin 75 shall have been deposited necessary in payment therefor.

The spring lifting-tongs D are especially constructed for the purpose in having the thumb or presser disks c at the upper end 85 thereof, the lower ends of the arms of said tongs having gripping-fingers d for convenience in taking hold of the cigar. One of the fingers d has pivoted thereto a protecting-loop e, through which the opposite finger extends, the pivoting of the loop enabling it to yield when the two gripping-fingers are brought down against the sides of the cigar and prevent bruising the same. The pivoted loop e also acts as a stop to prevent the gripping-fingers d from being forced down too far into the box of cigars, thereby preventing the danger of breaking or otherwise injuring any of the cigars in the box, the loop also serving as a stop to prevent the fingers from spreading too far apart.

The upper end of the spring-tongs D ex-

tends up through a slot *f* in the top of the show-case *A* a sufficient distance to be in convenient reach by the hand of the operator.

To prevent the boxes of cigars from sliding 5 off the tray *B*, the same is provided with a flange *g*, or any other means may be employed for this purpose, and the show-case may be provided with a suitable door *G*, with means for locking it closed, whereby the 10 empty boxes may be removed and replaced by filled boxes.

After the cigar has been removed from the box and deposited on the sliding table *E*, as hereinbefore described and shown in Fig. 2 of the drawings, a coin of suitable denomination is deposited through the slot *h*, which will fall into the coin-chamber *i* at the front end of the table. This chamber *i* is of substantially the same circumference as that of the coin and 20 is bottomless; but the coin is temporarily held in the chamber by the stationary plate *I*, which forms a temporary bottom to the chamber, as shown in Fig. 2 of the drawings. This table *E*, with its slot *h* and coin-chamber *i*, may be of any suitable form and construction that will serve the purpose intended. This sliding table *E* has rigidly connected thereto a suitably-shaped frame *J*, which frame is provided with a hopper *K* and a coin-receiver *L*, of any suitable and preferred construction, said receiver being connected to the frame *J* by a pin *k* or by any other desirable means, the table *E*, frame *J*, hopper *K*, and the coin-receiver *L* all moving together. 25

30 The coin-receiver *L* is bottomless, but when in position shown in Fig. 2 of the drawings in the box *M* will form a temporary bottom thereto to hold the coin in the receiver.

The sliding table *E* has connected to its 40 front end a thumb-piece *l* for operating it, and when it is pushed in the direction of the arrow in Fig. 2 of the drawings and when the table is released the coiled spring *m* on the guide-rod *n* will automatically force the table back to its normal position, thereby providing a spring-actuated sliding table both simple and effective in its operation. The thumb-piece *l*, which in reality is a receiving-plate for the cigar, performs this double function in providing means for operating the sliding table *E* and as a receptacle for the cigar as it leaves the machine.

The stationary plate *I* and the stationary box *M* are provided with slots *o p*, respectively, and the sliding table *E* with a slot *r*, into which extends a spring-trip *N*. A plate *s*, which forms a part of the sliding table *E* has a stop *t*, as shown more clearly in Fig. 4 of the drawings, said stop acting in conjunction 55 with the spring-trip *N*.

As the cigar is selected and deposited on the table *E* or the plate *s*, which is a part of the table, a coin of the required denomination is deposited in the slot *h* and will fall 60 into the coin-chamber *i*. As the sliding table *E* is forced outward in the direction of the

arrow, as shown in Fig. 2 of the drawings, the edge of the coin will act as a wedge and when brought in contact with the spring-trip *N* will force the same out laterally free from contact with the stop *t* on the plate *s*, which will allow the sliding table to be forced forward to its greatest extent, as shown in dotted lines in Fig. 2 of the drawings. 70

The box *M* forms a guide for the coin-receiver *L* and not only has a slot *p* in its bottom but an elongated opening or slot *u* at its top, with which engages the pin *k*. 75

When the table *E* has been forced forward, as shown in Fig. 3 of the drawings, the coin-chamber *i* and hopper *K* will register with the opening or slot *o* in the stationary plate *I*. This will admit the coin to pass from the chamber into the hopper, as shown in full lines, the coin being prevented from falling 80 into the receiver *L* by taking a position in the hopper transversely to the slot *u* in the top of the guide-box *M*. When this movement of the sliding table *E* has been completed, the parts will assume the position indicated 85 in full lines of Fig. 3 of the drawings, and before the coin can be deposited in the coin-receiver *L* the lower end of the hopper must pass beyond the end of the box *M*. This is automatically accomplished by the action of 90 the spring *m*, which will force the sliding table *E* back to its normal position and carry with it the hopper *K* to the position shown in dotted lines, the coin then falling into the receiver *L*, as indicated. The coin thus left 95 in the receiver *L* will not be deposited in the cash-box *P* until the table *E* is again forced forward to bring the receiver on line with the slot *p* in the guide-box *M*, when the coin will 100 be free to drop into the cash-box. A second 105 coin is necessary to be deposited before the sliding table can be operated, as the deposited coin acts on the spring-trip *N* to force it out laterally, so as to prevent the stop *t* from coming in contact therewith and admit of the 110 table being forced outward its greatest extent.

Without a coin is deposited, as herein described, the spring-trip *N* would remain in its normal position and when the table *E* was attempted to be operated the stop *t* would 115 strike the spring-trip *N* and prevent any further movement of the table.

When the table *E* is moved forward, as indicated in full lines of Fig. 3 of the drawings, the cigar will be deposited on the receiving-plate *l* by dropping down thereon, and the backward movement of the table caused by the action of the spring *m* will bring the receiving-plate in position where the cigar can 120 be taken out by the purchaser.

The bottom of the show-case *A*, I have shown at *O*, and said case may be supported upon suitable legs *R*, and, if desired, the upright rod *a*, which operates the rotatable tray *B*, may have its bearing in suitable nuts *S T*, 125 connected together by screw-threads, as shown in Fig. 6 of the drawings, or any other suit-

able means may be substituted for that shown.

The coin-receiver L may have a glass front v and the cash-box P a glass front w for inspection of the interior thereof, as found desirable.

The nuts S T are formed with clamping-disks U V, respectively, between which the glass sections forming the top of the show-case are held, said sections being shown at W.

I do not wish to be understood as confining myself to any special form of show-case or any particular means for operating the rotatable tray B, and many changes or modifications in the several details of construction may be resorted to without departing from the principle of the invention.

The cash-box is provided with a suitable door x, with means for locking the same to secure the contents thereof as well as enabling the contents to be removed.

Wire or other suitable supports X, having a hooked upper end, are used to hold the box-lid open, as shown in Fig. 2 of the drawings.

Having now fully described my invention, what I claim as new, and desire to secure by Letters Patent, is—

1. A coin-controlled vending-machine, consisting of a coin-controlling device consisting of a suitable slidable table provided with a coin-chamber and a stop, a locking and releasing device for the table, a suitable frame with a hopper and a coin-receiver connecting with the table and movable therewith, and a slotted guide-box for the receiver, substantially as and for the purpose described.

2. A coin-controlled vending-machine, consisting of a coin-controlling device connecting with the show-case and consisting of a cash-box, a stationary slotted guide-box located therein, a slidable table provided with a coin-chamber and means for locking or releasing said table, a slotted stationary supporting-plate for the slidable table, a suitable hopper and coin-receiver connecting with the table, and a slotted guide-box for containing the

coin-receiver and operating substantially as and for the purpose specified.

3. A coin-controlled vending-machine, consisting of a coin-controlling device consisting of a slidable and spring-actuated table provided with a coin-chamber and a stop, a spring-trip for locking or releasing the table, a hopper and coin-receiver connecting with the table and moving therewith, a slotted supporting-plate for the table; and a guide-box for the coin-receiver having slots at both top and bottom, substantially as and for the purpose specified.

4. A coin-controlled vending-machine comprising a sliding table constructed with a bottomless chamber, a chute leading to the coin-chamber, a receiving-plate at the front end of the table, and a plate having a stop and providing a slot, the pendent spring-trip projecting into the slot and released from the stop by the coin, a stationary plate beneath the table, having a coin-slot through which the coin drops, and a coin-receptacle located beneath the stationary plate.

5. A coin-controlled vending-machine comprising a sliding table constructed with a bottomless coin-chamber, a chute leading to the coin-chamber, a receiving-plate at the front end of the table, and a plate having a stop and providing a slot, the pendent spring-trip projecting into the slot and released from the stop by the coin, a stationary plate beneath the table having a coin-slot through which the coin drops, a frame provided with a hopper and a bottomless coin-receiver beneath the hopper, and rigidly secured to the table, and a stationary box having a coin-slot and located beneath the coin-receiver.

In testimony that I claim the above I have hereunto subscribed my name in the presence of two witnesses.

DAVID K. STONE.
